COMPRESSOR UNLOADING DEVICE

Burton S. Aikman, Wilkinsburg, Pa., assignor to
 The Westinghouse Air Brake Company, Wil-
 merding, Pa., a corporation of Pennsylvania

Application May 15, 1936, Serial No. 79,938

1 Claim. (Cl. 230—27)

This invention relates to fluid compressor unloading devices, particularly unloading devices effective to unload the compressor as long as the speed of the compressor does not exceed a certain uniform speed, and automatically operative to load the compressor when the compressor speed exceeds the certain uniform speed.

The principal object of my invention is to provide a novel arrangement whereby a compressor unloader device is controlled automatically according to the speed of the compressor. More specifically, the novel arrangement provides for control of the unloader device according to the degree of partial vacuum produced in the crank case of a compressor by operation of the compressor.

The above and other objects of my invention which will be made apparent subsequently are attained by an illustrative embodiment of the invention hereinafter described and shown in the accompanying drawing wherein the single figure is a fragmentary view, mostly in section, showing my unloader device and its arrangement with a compressor.

Referring to the drawing, the compressor shown comprises an upper casing section forming a compression cylinder 1, and a lower casing section forming a piston guide cylinder 2 and a crank case chamber 3. Projecting from the guide cylinder 2 is an annular flange 4 of L cross section, the end flange 6 on the compression cylinder 1 cooperating with the upper edge of the flange 4 and being suitably secured thereto as by bolts, not shown. The flange 4 forms an annular space 5 or chamber 7 which is open to atmosphere through one or more ports 5 in the flange.

The bore 9 of the compression cylinder 1 is larger than the bore 11 in the guide cylinder 2 and opens at its lower end into the chamber 7, hereafter called the intake chamber.

A piston 13 is provided having a pressure head 14 slidable in the bore 9 and a guide flange or skirt 15, of smaller diameter than the head 14, slidable in the bore 11. The piston 13 may be reciprocated in the well known manner by rotation of a crank shaft 17, the crank shaft having an eccentric 18 connected by a connecting rod 19 to a wrist pin 21 on the piston.

Any suitable type of intake valve may be provided for admitting air into the compression chamber 22 as for example, a ring valve 23 mounted on the piston head 14 for controlling a series of intake ports 24 which extend through the outer periphery of the pressure head of the piston. On

the up or compression stroke of the piston, the ring valve 23 moves into seated position to close the ports 24 and, on the down or intake stroke of the piston, unseats to admit air from the intake chamber 7 to the compression chamber 22 through the ports 24.

Any suitable type of discharge valve may be provided, as for example, a spring loaded disc valve 27 for closing the discharge port 28, opening out of the compression chamber 22, on the intake or down stroke of the piston, and for permitting the flow of fluid compressed in the compression chamber 22 out through the discharge port to a discharge pipe 29, on the compression or up stroke of the piston.

According to my invention, I provide an unloader valve device 32 interposed in the discharge pipe 29 between the compressor and a suitable reservoir 33.

The unloader valve device 32 comprises a casing 34 which may be mounted conveniently as a separate unit, in any desired location or which may constitute an integral or attached part of the compressor casing.

Formed in the casing 34 is a chamber 36 open to the portion of the discharge pipe 29 leading to the reservoir 33 and containing a spring loaded check valve 37 for preventing back flow from the reservoir 33 to a passage or chamber 38, to which is connected the portion of the discharge pipe 29 leading from the compressor. The passage 38 opens through a port 39 into a bore 41 in the casing, which bore is constantly open to atmosphere through a port 42. A pin valve 44 is provided for closing the port 39 and is formed on the end of the stem 46 of an operating piston or movable abutment 47 which is contained in a bore 48 that is open at the outer end thereof to atmosphere, the casing having an inwardly extending flange 49 at the outer end of the bore 48 for limiting the movement of the piston 47 outwardly of the bore.

A relatively lightly tensioned return spring 51, interposed between the inner face of the piston 47 and the casing 34 in an annular chamber 52 surrounding the stem 46 of the piston, yieldingly urges the piston outwardly of the bore 48 to unseat the pin valve 44 and open port 39. The chamber 52 is constantly connected to the crank case chamber 3 of the compressor as by a pipe, 50 conduit, or passage 53.

Any suitable device for producing a partial vacuum in the crank case chamber 3 by operation of the compressor may be provided, as for example the check valve device 54 in the pres-

sure head 14 of piston 13. The check valve device 54 comprises a ball valve 55 adapted to seat on a conical valve seat 56 to close a port 57 through the pressure head of the piston 13, upon the up 5 or compression stroke of the piston. The ball valve 55 is contained in a recess 59 of a screw plug 61 removably secured to the piston head 14, the recess 59 being open to the compression chamber 22 through a plurality of ports 62. On the 10 down or intake stroke of the piston 13, the ball valve 55 unseats and permits air to pass from the crank case chamber side of the piston into the compression chamber 22.

It will be understood that upon continued 15 reciprocation of the piston 13, air is continually forced out of the crank case chamber 3 into the compression chamber 22 past the check valve device 54, while back flow of the air from the compression chamber to the crank case chamber is prevented. Thus the pressure in the crank case 20 chamber is reduced, that is, a partial vacuum is produced therein.

In order to prevent the creation of a partial 25 vacuum in the crank case chamber until the speed of the compressor exceeds a certain desired speed, a restricted passage 65 is provided which connects the crank case chamber 3 to atmosphere, and which may be suitably located and so designed that until the speed of the compressor, that is the 30 rapidity with which the piston 13 is reciprocated, exceeds a certain uniform speed, the rate of influx of air through the passage 65 into the crank case chamber 3, may equal the rate at which it is taken out of the crank case chamber by operation of the 35 check valve device 54. Thus until the speed of the compressor exceeds the said certain uniform speed, as on starting, the crank case chamber remains at atmospheric pressure. Thereafter, as the speed of the compressor increases, the rate at 40 which air is discharged from the crank case chamber by operation of the check valve device 54 exceeds the rate at which it is capable of flowing into the crank case chamber through the passage 65 and consequently a partial vacuum is produced in the crank case chamber, the degree of 45 vacuum increasing with the increase in speed of the compressor above the certain uniform speed.

Conversely, as the speed of the compressor reduces below the certain uniform speed, atmospheric pressure is restored in the crank case 50 chamber.

In operation, with the compressor at rest, the pin valve 44 of the unloader device 32 is unseated to open port 39 and thus open the compressor side 55 to pipe 29 and passage 38 of the unloader device to atmosphere through port 42, the check valve 37 being effective to prevent back flow of air from the reservoir 33 into passage 38 and to atmosphere. It will be understood, that when the crank case chamber is at atmospheric pressure, as it 60 is when the compressor is stopped, then the annular chamber 52 of the unloader device is also at atmospheric pressure, and thus that spring 51 acts to shift the piston 47 outwardly and thus 65 unseats the pin valve 44.

As the compressor begins to operate no partial 70 vacuum is created in the crank case chamber until the certain uniform speed is exceeded, this uniform speed depending upon the flow capacity of the restricted passage 65. As the degree of partial 75 vacuum increases after the compressor exceeds the certain uniform speed, a fluid pressure unbalance is created on the piston 47 of the unloader, due to the fact that annular chamber 52

is at a lower pressure than the atmospheric pressure acting on the outer face of the piston 47, which lower pressure corresponds to the degree of partial vacuum in the crank case chamber. When a sufficient differential fluid pressure force 5 is effective on the piston, as for example five to ten pounds, the piston moves upwardly in bore 48 to cause the pin valve 44 to close port 39. Communication between the compressor portion of discharge pipe 29 and atmosphere being thus cut off, the fluid compressed by the compressor and discharged into pipe 29 can only escape past the check valve 37 into the reservoir 33. Thus loading of the compressor is effected only after the compressor has exceeded a certain predetermined 10 speed.

Obviously, the greater the degree of vacuum produced in the crank case chamber and in annular chamber 52, the greater is the differential fluid pressure force acting on the piston 47 to hold pin 20 valve 44 seated. However, even at the minimum degree of vacuum in crank case chamber 22 which will cause seating of the pin valve 44, the force holding the pin valve seated is sufficient to resist unseating of the pin valve 44 due to maximum 25 fluid pressure acting in passage 38 on the inner seated or end face of the pin valve 44. Observation of the relatively small area of the pin valve 44 and the relatively large area of the piston 47 will render this fact readily apparent. It will be 30 understood that by increasing the area of the piston 47, the piston will be responsive moved to seat the pin valve 44 at a lower degree of partial vacuum in the crank case and consequently a lower speed of operation of the compressor. Thus 35 by coordinating the flow capacity of the restricted passage 65 and the area of the piston 47, the pre-determined speed beyond which it is necessary for the compressor to operate before loading is effected, may be made any selected speed. 40

When the speed of the compressor decreases, as a result of an increase in load thereon or of stopping the compressor, the degree of partial vacuum in the crank case decreases accordingly, and when the speed of the compressor has decreased 45 sufficiently so that the differential fluid pressure force acting on the piston 47 is inadequate to hold the pin valve 44 seated against the force of the fluid pressure in passage 38 acting on the end of the pin valve 44, the piston will be moved 50 outwardly, assisted by the tension of the return spring 51, to unseat the pin valve 44 and open to atmosphere that portion of discharge pipe 29 leading from the compressor, the compressor 55 being thereby unloaded.

The spring 51 is, as previously stated, only lightly tensioned and may be omitted if desired, since the piston 47 will be actuated to seat and unseat the pin valve 44 without the spring 51 being present. 60

It will accordingly be seen that I have devised an arrangement including an unloader valve device for a fluid compressor, which unloader is automatically controlled by the degree of partial vacuum produced in the crank case chamber of the compressor and dependent upon the speed of the compressor, for unloading the compressor when the speed of the compressor decreases below a certain uniform speed and for loading the compressor when the speed of the compressor increases above the certain uniform speed. 70

I appreciate that various omissions, additions or modifications may be effected with respect to 75

the embodiment shown, without departing from the spirit of the invention. For example, a governor device operated according to the speed of the compressor may be provided for closing the restricted passage 65 after the unloader device 32 has operated to load the compressor, so that as long as the compressor continues to operate above a certain speed, the passage 65 will be closed and thus enable a relatively high degree of partial vacuum to be produced in the crank case chamber and in chamber 52 of the unloader device 32, to the end that the higher fluid pressure differential acting on piston 47 will more positively hold the pin valve 44 seated against leakage therewith.

It is not my intention, therefore, to limit the scope of my invention except as necessitated by the scope of the prior art.

Having now described my invention, what I claim as new and desire to secure by Letters Patent, is:

In combination, an air compressor comprising a compression chamber, a crank case chamber, a reciprocating piston effective to compress air in 25 said compression chamber, a check valve in the

pressure head of the piston effective upon reciprocation of the piston to cause withdrawal of air from the crank case chamber to the compression chamber and thereby tend to cause a partial vacuum in the crank case chamber, a restricted passage through which air may flow into the crank case chamber at any rate up to a maximum rate, said check valve being ineffective to produce a partial vacuum in the crank case chamber unless the speed of operation of the compressor exceeds a certain uniform speed beyond which the rate of withdrawal of air from the crank case chamber by said check valve exceeds the maximum rate of flow of air into the crank case chamber through said restricted passage, the degree of the partial vacuum created in the crank case chamber varying in accordance with the speed of the compressor above the certain uniform speed, and means effective to unload the compressor as long as the partial vacuum in the crank case chamber does not exceed a certain predetermined degree and operative when the partial vacuum exceeds said certain degree to cause loading of the compressor.
